United States Patent

Des. 239,190
Patented Mar. 16, 1976

239,190

SKI BINDING

Burton A. Weinstein, New York, and Gordon C. Lipe,
Skaneateles, N.Y., assignors to National Recreation
Industries, Inc.

Filed May 20, 1974, Ser. No. 471,667

Term of patent 14 years

Int. Cl. D21—02
U.S. Cl. D34—14 D

FIG. 1 is a perspective view of a ski binding showing my new design;

FIG. 2 is a side elevational view thereof showing the side opposite that shown in FIG. 1;

FIG. 3 is a bottom plan view thereof;

FIG. 4 is a front elevational view thereof; and

FIG. 5 is a rear elevational view thereof.

We claim:

The ornamental design for a ski binding, as shown.
